UNITED STATES PATENT OFFICE.

THOMAS B. WYMAN, OF MUNISING, MICHIGAN.

BALLOT-BOX.

1,277,811.

Specification of Letters Patent. Patented Sept. 3, 1918.

Application filed June 17, 1918. Serial No. 240,485.

To all whom it may concern:

Be it known that I, THOMAS B. WYMAN, a citizen of the United States, residing at Munising, in the county of Alger and State 5 of Michigan, have invented a new and useful Ballot-Box, of which the following is a specification.

The object of my invention is to provide a ballot box having novel means for locking, without the use of a padlock; and to provide a lock which effectively fills the only opening in the ballot box, when closed.

It is an especial object of my invention to provide a ballot box which complies with 10 the laws of the State of Michigan as to its construction and method of locking.

I attain the object of my invention by the mechanism illustrated in the accompanying drawings, in which—

20 Figure 1 is a section on line I—I of Fig. 3 with the official seal applied over the ballot opening;

Fig. 2 is a top plan of the invention with the seal open;

25 Fig. 3 is a vertical section through the ballot box;

Fig. 4 is a top plan of the ballot box cover in locked position; and

30 Fig. 5 is a detailed sectional view of the lock seal.

Like letters designate like parts in each of the views.

Referring to the accompanying drawings, I provide a suitable ballot box F, having 35 a segmental or half cover G, on which is mounted a lock C of any suitable construction having a keyhole E and a bolt D as shown in Fig. 1. I provide a suitable removable cover H for the ballot box, and in 40 cover H I provide a raised portion, or pocket A to receive lock C when the cover is in the position shown in Fig. 3. I further provide a ballot opening B on the opposite side of the ballot cover H, this opening being of corresponding shape and slightly larger size than lock C, to receive that member when the ballot cover is turned about to the position shown in Fig. 4, which is the reverse of that shown in Fig. 3.

50 As shown in Fig. 1, a suitable seal S may be fastened over the ballot opening, the seal being engaged by suitable members I, such

as the wires shown or a raised section of the box cover having a similar function. When the cover of the ballot box is in locked position, as shown in Fig. 4, the keyhole E may be protected by a suitable seal K, as shown in Fig. 5, which is inserted through openings J in lock C.

In use, the ballot box appears as shown 60 in Fig. 2, the ballots being inserted through the opening B, while the lock extends into the pocket A as shown in Figs. 1 and 3. The ballot opening B is of the proper size to admit a single closed ballot, as required 65 by the laws of Michigan. When the balloting is concluded, the cover H is turned or rotated half way around so that the lock C will project through and close the ballot opening B. The lock is then turned, causing 70 the bolt D to project over the cover H, which prevents withdrawal of the cover as the lock C is mounted on the segmental portion G of the body of ballot box F. A suitable seal K is then secured over keyhole E 75 by the proper official as provided by the general election laws of the State. This method of locking the ballot box prevents tampering with the ballots as the only opening into the ballot box is effectively filled by 80 the lock. My invention also does away with the old padlock system, while still complying with the laws of the State of Michigan, to meet which this ballot box is primarily designed, while offering absolute protection 85 to the ballots.

What I claim is:

1. A ballot box arranged to prevent tampering with the ballots, comprising a box having a segmental cover portion, a lock 90 mounted on said segmental cover portion, a removable cover engaging over the entire upper portion of the ballot box, the said cover having a ballot opening, a raised pocket positioned to receive the lock, the ballot 95 opening being shaped to snugly receive the lock when the removable cover is moved to reverse position, whereby the lock will close the only opening into the ballot box.

2. A ballot box designed to afford protection from tampering and having in combination a box having a half cover integral therewith, a lock affixed to the half cover, a removable cover adapted to engage over the 100

entire upper portion of the ballot box, said cover having a pocket corresponding in size with the lock and shaped to receive same, the cover also having a ballot opening shaped to receive one folded ballot, said ballot opening corresponding in shape with the lock and being of such size as to snugly re-

ceive same when the cover is moved to reverse position with the ballot opening disposed over the integral half cover of the box to entirely close the box, and means on the cover for sealing the ballot box, substantially as shown and described.

THOMAS B. WYMAN.
